UNITED STATES PATENT OFFICE.

EDGAR W. GENT, OF NEW YORK, N. Y., ASSIGNOR TO WESTERN ELECTRIC COMPANY,
INCORPORATED, OF NEW YORK, N. Y., A CORPORATION OF NEW YORK.

ELECTRICAL REGULATING DEVICE.

1,383,799.

Specification of Letters Patent. Patented July 5, 1921.

Application filed May 1, 1920. Serial No. 378,330.

To all whom it may concern:

Be it known that I, EDGAR W. GENT, a citizen of the United States, residing at New York, in the county of New York, State 5 of New York, have invented certain new and useful Improvements in Electrical Regulating Devices, of which the following is a full, clear, concise, and exact description.

This invention relates generally to electrical regulating devices and more particularly to such devices employing a multiplicity of stationary contacts, all of which are accessible to a common movable contact. The adaptation of this invention is not confined to any one specific type of apparatus, but, on the contrary, it may be embodied in a number of different types of apparatus such, for instance, as rheostats, potentiometers, variable inductance and variable capacity apparatus, etc.

The object of this invention is the provision, in connection with such devices as enumerated above, of a simple self-centering combination contact and terminal which will 25 reduce the cost of production of such apparatus, and eliminate the positive stop or so-called clicking device ordinarily employed therewith.

The principal feature of the invention resides in the combination with a movable contact member of a combined stationary contact and terminal in which the stationary contact medium serves to secure the terminal, and also to provide a seating contact 35 for the movable contact member. Other features of the invention will be brought out in the detailed description.

In ordinary practice it is customary to provide, in connection with multiple contact electrical apparatus as noted above, positive stopping devices or so-called clicking devices which indicate to the operator when the movable contact is properly centered. These clicking devices also tend to 45 prevent the movable contact arm stopping in mid-position, that is between contacts. Such devices, being well known in the art, require no description here. This invention eliminates the necessity for a separate clicking device, the function of which is performed thereby without the use of any device or parts other than are required for the performance of other necessary functions of the apparatus.

55 A potentiometer, illustrating one embodiment

of this invention, is shown in the accompanying drawing, in which Figure 1 is a perspective view of the potentiometer, some parts, being shown fragmentarily for the sake of clearness. Fig. 2 is a bottom 60 plan view of the potentiometer and Fig. 3 is a perspective cross sectional view of a terminal and eyelet, together with the end portion of a movable contact arm.

Journalized in the bearing 14 is a shaft 1, 65 to one end of which is securely attached an arm 2 and to the other end of the shaft a handle 3, by means of which the shaft and arm are rotated. Attached to the bearing 14 is a spider 12, to which, in turn, is attached a tubular member 5, preferably of insulating material. Mounted on the exterior surface of the tubular member 5 are two rows of terminals 6 which are securely fastened to the tubular member by means of the metal eyelets 4 which extends through apertures in the terminals 6, and also through apertures in tubular member 5. After being assembled, the eyelets 4 are headed over as illustrated in Fig. 3. Mounted in a recess in the end portion of arm 2 is a metal ball 7 and a helical spring 5 for pressing the ball 7 outwardly. The ball 7 will firmly seat itself in the aperture of any of the eyelets 4 with which it is brought into contact as illustrated in Fig. 3. When shaft 1 and arm 2 are rotated, the ball 7 will drop into the aperture of each eyelet which it passes in its journey, and upon dropping into the aperture of an eyelet it 80 will emit a distinct click, indicating to the operator that the ball is properly centered on one of its contacts. In the apparatus illustrated only the upper row of eyelets make contact with the ball 7, the lower row 85 of eyelets being provided only for securing the lower terminals to the tubular member 5. Two additional terminals 9 are attached to the exterior of the tubular member 5, each of which serves as a terminus for the 90 resistance wire 8 which is passed alternately from one row of terminals to the other, and soldered or otherwise secured to the terminals 6. Terminal 10 is electrically connected with the ball 7 through the medium of 95 shaft 1 and arm 2, and is therefore electrically connected with both terminals 9 through the medium of any of the eyelets 4, and its terminal 6 with which the ball 7 100 may happen to be in contact and the resist- 110

2
ance wire 8. Depending from the spider 12, and interposed in the path of arm 2, is a lug 13 for limiting the movements of the arm. A perforated metal guard 11 supported by spider 14 provides mechanical protection for the resistance wire 8. The potentiometer is intended to be mounted on a panel board, not shown, by means of apertures 15. When mounted, the handle 3 and pointer 16 project through the panel.

What is claimed is:

1. In an electrical regulating device, a movable contacting member, a supporting member, a plurality of terminals on said supporting member, an eyelet for each terminal extending through said terminal and said supporting member said eyelet being formed to provide a positive seating contact for said contacting member and a conducting medium connected to said terminals.
2. In an electrical regulating device, a rotatable contacting member, a tubular supporting member, a plurality of terminals on said supporting member, an eyelet for each terminal extending through said terminal and the wall of said supporting member, said eyelet being formed to provide a positive seating contact for said contacting member, said eyelets being permutably accessible to said contacting member and a conducting medium connected to said terminals.
3. A variable resistance device comprising a tubular supporting member of non-conducting material, a shaft concentric with said

supporting member, a contacting arm attached to said shaft and rotatable therewith, a plurality of terminals mounted on the exterior of said supporting member, an eyelet for each terminal, extending through said terminal and the wall of said supporting member, said eyelet being formed at its inward end to provide a positive seating contact for said contacting arm, said eyelets being permutably accessible to said contacting arm and a resistance medium connected to said terminals.

4. A variable resistance device comprising a tubular supporting member of non-conducting material, a shaft, concentric with said supporting member, a contact arm attached to said shaft and rotatable therewith, a resiliently supported contact ball at the outward end of said contact arm, a row of terminals mounted on the exterior of said supporting member, an eyelet for each terminal, extending through said terminal and the wall of said supporting member said eyelet being formed at its inward end to provide a positive seating contact for said contact ball, said eyelets being permutably accessible to said contact ball, a second row of terminals mounted on the exterior of said supporting member and parallel with said first row, and a resistance wire connected alternately to the terminals of each row.

In witness whereof, I hereunto subscribe my name this 27th day of April, A. D. 1920.

EDGAR W. GENT.
